[57] CLAIM

The ornamental design for a phototherapy cabinet for longwave ultraviolet light treatment, substantially as shown and described.

DESCRIPTION

FIG. 1 is a front elevational view of the phototherapy cabinet for longwave ultraviolet light treatment embodying my new design in a closed position; FIG. 2 is a top plan view of the phototherapy cabinet shown in FIG. 1; FIG. 3 is a bottom plan view of the phototherapy cabinet shown in FIG. 1; FIG. 4 is an interior elevational view of the phototherapy cabinet in an open position; and, FIG. 5 is a cross-section taken on line 5—5 of FIG. 1.
